UNITED STATES PATENT OFFICE.

CHARLES NURNBERG, OF BROOKLYN, NEW YORK.

THERMOMETER AND CASING THEREFOR.

Application filed October 16, 1922. Serial No. 594,838.

To all whom it may concern:

Be it known that I, CHARLES NURNBERG, a citizen of the United States, and a resident of the city of New York, borough of Brooklyn, in the county of Kings and State of New York, have invented a new and Improved Thermometer and Casing Therefor, of which the following is a full, clear, and exact description.

10 This invention relates to improvements in casings or holders for thermometers and other like instruments, and has particular reference to a casing which may be conveniently carried about in the pocket of 15 the user.

An object of the invention is to provide a casing in which a thermometer may be mounted without engaging the walls of the casing, and which may be securely maintained in the casing when in use so that 20 actual handling of the thermometer during the taking of temperature may be avoided.

The above and other objects will appear more clearly from the following detail description, when taken in connection with 25 the accompanying drawing, which illustrates a preferred embodiment of the inventive idea.

In the drawing—

30 Figure 1 is a vertical longitudinal section illustrating the manner of mounting the thermometer in the casing when not in use;

Figure 2 is a perspective view of the 35 thermometer retaining means positioned within the casing; and

Figure 3 is an enlarged transverse section on the line 3—3 of Figure 1.

In the embodiment of the invention illustrated 40 the casing comprises a body portion 4 of cylindrical formation and provided with a removable end closure 5 at one end, the other end of said body portion being open. Adjacent the open end of the body portion 4 the same is provided with external threads 6 cooperating with similar threads formed upon the interior of the cap 7 to maintain said cap in closing position. The cap is also provided with a removable 45 end closure 8 and a clip 9, which may be utilized in attaching the holder or casing in the pocket of the user.

In practice, thermometer casings of this character are preferably made in sets and 50 the end closures 5 and 8 of the different casings of each set may be of any suitable

material and of different colors to distinguish the different uses to which the thermometers of the set are adapted.

The invention contemplates the provision of means within the body portion 4 for engaging a portion of the thermometer 9 remote from the bulb 10 thereof to space the thermometer from the walls of the body portion and to frictionally maintain said thermometer against longitudinal movement with respect to the body portion when either end of the thermometer is inserted into said body portion. This means preferably comprises a retaining member made 70 of any suitable material having a certain degree of flexibility and including a split sleeve 11 and a pair of opposed gripping fingers 12 and 13 extending longitudinally from the sleeve member and normally converging toward their free ends, which are slightly bent transversely to conform to the contour of the thermometer 9, which, as shown in Figure 3, is substantially triangular in cross section. The retaining member is preferably mounted within the body portion 4 with the sleeve 11 positioned at the open end of said body portion and the fingers 12 and 13 extending inwardly to a point where the same will engage the thermometer 9 adjacent its end and at a point 75 remote from the bulb 10 so that when the thermometer is in position in the body portion there will be nothing therein to contact with the bulb when the same is not in use. When the thermometer is in position within the casing, the thermometer is engaged by the gripping fingers 12 and 13 throughout the entire lengths thereof, whereby to increase the effective gripping 80 surfaces and thereby produce a maximum frictional engagement between the parts. By positioning the retaining member as described, it will be obvious that when either end of the thermometer is inserted into the 85 casing the same is immediately centered therein and prevented from lateral movement with respect to the walls of the casing, thus insuring against any possibility of the thermometer, and particularly the bulb 10 thereof, engaging said walls which might otherwise result in the deposit of 90 germs thereon after the thermometer has been used in contagious cases.

When it is desired to use the thermometer 9 the cap 7 may be first unscrewed from the body portion and the thermometer then re-

removed from said body portion and again inserted thereinto in a reversed position with the bulb 10 extending beyond the end of the body portion. The temperature may then be taken by employing the body portion as a handle and in this manner the thermometer may be used with a minimum danger of a spread of contagious diseases. When the thermometer is reversed within the body portion as described, the resilient fingers 12 and 13 will grip the thermometer in the manner illustrated in Figure 3 and as above described and effectively prevent the same from moving longitudinally of the body portion and thus becoming accidentally detached therefrom.

From the foregoing description it will be apparent that the invention provides a casing or holder for a thermometer, such as a clinical thermometer, which is extremely neat in appearance, simple in construction, and which may be readily and conveniently carried about the person of the user.

What is claimed is:

1. In a device of the character described, a casing including a body portion for receiving either end of a thermometer and a single thermometer engaging member positioned within said body portion and formed of a single piece of resilient material extending from one end of said body portion to a point intermediate its ends and engaging throughout its length a portion of said thermometer remote from the bulb thereof and functioning alone to space the thermometer from the walls of said body portion and to frictionally maintain said thermometer against longitudinal movement with respect to said body portion when either end of the thermometer is inserted into said body portion.

2. In a device of the character described, a casing including a body portion for receiving either end of a thermometer, and a single retaining member including a sleeve positioned at one end of said body portion, and opposed gripping fingers extending longitudinally from said sleeve to a point intermediate said body portion and engaging said body portion throughout their lengths, said sleeve and fingers engaging said thermometer at a point remote from the bulb thereof and functioning alone to space the thermometer from the walls of said body portion and prevent longitudinal movement of said thermometer in said body portion when either end of the thermometer is inserted thereinto.

3. In a device of the character described, a casing including a body portion for receiving either end of a thermometer, a single retaining member including a sleeve positioned at one end of said body portion, and opposed gripping fingers extending longitudinally from said sleeve to a point intermediate said body portion, said sleeve and fingers engaging said thermometer at a point remote from the bulb thereof and functioning alone to space the thermometer from the walls of said body portion and prevent longitudinal movement of said thermometer in said body portion when either end of the thermometer is inserted thereinto, said gripping fingers being bent transversely to conform to the contour of said thermometer.

CHARLES NURNBERG.
